CLAIM

The ornamental design for an applicator with slide ring activator, as shown and described.

DESCRIPTION

FIG. 1 is a top plan view of an applicator with slide ring activator showing my design;

FIG. 2 is a bottom plan view thereof;

FIG. 3 is a left side elevational view thereof, the side opposite being a mirror image of the side shown;

FIG. 4 is a front elevational view thereof;

FIG. 5 is a rear elevational view thereof; and,

FIG. 6 is a perspective view thereof.
